UNITED STATES PATENT OFFICE

OLIVER S. BOWMAN, OF COLORADO SPRINGS, COLORADO

GRATE

Application filed May 4, 1931. Serial No. 534,851.

This invention relates to improvements in combustion devices for burning coal and has reference more particularly to the grate used in connection with furnaces, boilers and heaters of all types.

It is an object of this invention to produce a grate of such construction that it shall be especially well adapted for use with self-feeding furnaces that employ slack coal or coal that has been crushed to reduce its size.

Another object of this invention is to produce a grate that shall have means for agitating parts thereof in such a way that the fire can be cleaned of ashes and clinkers without seriously disturbing the fire bed.

The above and other objects that may become apparent as this description proceeds are attained by means of a construction and an arrangement of parts that will now be described in detail and for this purpose reference will be had to the accompanying drawing in which the preferred embodiment of the invention has been illustrated and in which:

Fig. 1 is a diametrical section through a furnace equipped with my improved grate;

Fig. 2 is a top plan view taken on line 2—2, Fig. 1, and shows a sector of the grate;

Fig. 3 is a section taken on line 3—3, Fig. 2, and shows the manner in which the tiltable sections of the grate are mounted;

Fig. 4 is a section taken on line 4—4, Fig. 3;

Fig. 5 is a section taken on line 5—5, Fig. 4; and

Fig. 6 is a view showing the ring that is connected with the tiltable sections and which serves to tilt them about their axes.

In the drawing reference numeral 1 represents the surface of a floor or some other support and reference numeral 2 the bottom ring of the furnace. The upper edge of ring 2 is provided with a shoulder 3 on which is supported a ring 4 that forms the outer wall of the fire pot. The upper edge of ring 4 has a groove 5 within which is supported the upper or dome portion 6 of the combustion chamber. The parts just described are enclosed in a sheet metal jacket that is spaced from them so as to provide a

hot air passageway 7, all as is common in hot air furnace construction. Although this invention has been shown in connection with a hot air furnace, it is to be understood that the grate and the other parts that co-operate with it are equally well adapted for boilers or any other heating appliance.

Secured to the inner surface of ring 2, or cast integral therewith, is an inwardly extending flange 8 that serves as a support for the grate sections. The lower end of ring 4 extends inwardly a short distance from the inner surface of ring 2 so as to form an overhanging shoulder 9. The grate is composed of a number of sectors having upwardly inclined portions 10 that when they are assembled, form a conical surface such as indicated by reference numeral 11 in Fig. 1. The extreme tips of the several sectors are provided with inwardly projecting projections 12 that are adapted to project over a collar 13 on the upright support 14. This support has its lower end connected with a base 15 that rests on a supporting bar 16. The ends of bar 16 are secured to the inside of ring 2. The lower ends of the grate sections 10 are provided with outwardly extending projections that are formed from two spaced arms 17, whose outer ends are connected as indicated at 18. The two arms 17 are spaced apart as shown in Fig. 2 and the lower ends of sections 10 are provided with bearings 19, while the transverse portions 18 have bearings 20. The parts 17 are so related to the parts 10 that when the grate is in place, the parts 17 will lie in a horizontal plane. In the example illustrated, there are sixteen sections of grate and when these are assembled, they form a complete upwardly extending conical projection surrounding the support 14. Mounted on each outwardly extending radial projection is a rocking grate segment 21. These segments when assembled form an annular flat surface and each rocking grate segment is provided with trunnions 22 that engage in the bearings 19 and 20. Each rocking grate segment is also provided with a downwardly extending arm 23 that projects through the opening between member

100

17. The lower end of each arm 23 has a slot. The inner surfaces of the parts 24 on each side of the slot are convexly curved as indicated in Fig. 5. Supported on the 5 upright 14 and the upper end of the base 15 is a wheel having a hub 25 and spokes 26. The outer ends of the spokes are connected by means of a rim 27 and this rim is provided on its outer surface with a number of 10 radial projections 28, there being one projection for each rocking grate segment. The projections 28 extend into the slots and therefore when the wheel to which the projections are secured is rocked about its pivot, 15 it will impart simultaneous rocking motion to all of the rocking grate segments 21. A handle 29 is connected with the rim 27 and extends through slots in the ring 2 and in the sheet metal housing and when this 20 handle is moved back and forth, the grate segments 21 will be rocked about their trunnions.

In the embodiment shown the coal is fed into the furnace and onto the grate through 25 an inclined conduit 30. The upper end of this conduit may be connected with a hopper, which has not been shown, and the lower end is curved so as to terminate in a portion 31 having a vertical axis. The 30 axis of the portion 31 preferably coincides with the axis of the support 14. The conduit terminates a short distance above the upper surface of the grate so that the coal can flow downwardly along the conical grate surface until it reaches a predetermined thickness and as the coal burns it will automatically be replaced with coal from the conduit. In order to determine the thickness of the coal, a movable ring 32 has been 35 secured to the end portion 31. Portion 31 is provided with two diametrical slots 33 having notches 34 and the ring 32 has inwardly extending pins 35 that project through the slots and engage the notches, and in this 40 way the height of the ring and the thickness of the coal layer can be adjusted.

The furnace is preferably provided with a recess for the reception of the ashes as indicated in Fig. 1.

50 From the above description it will be seen that the grate that forms the subject of this invention consists of a central conical portion with its apex upwards and whose base is surrounded by an annular flat grate surface composed of a plurality of segments 21 that can be rocked simultaneously and which therefore serves to clean the fire of ashes and cinders and permit the latter to fall downwardly into the space below the grate. By rocking the segments 21, a better 55 cleaning action is obtained than if they were all connected together so as to form a ring as in the latter case only particles of such small size that they could pass through the 60 openings would pass into the ash pit.

This grate is especially well adapted for self-feeding furnaces of the type shown and has been found to be very efficient in operation.

Having described the invention what is 70 claimed as new is:

1. A grate for a coal burning device comprising, a central conical portion having its apex at the top, said conical portion being composed of a number of sectors provided at their lower ends with projections extending in a plane perpendicular to the axis of the conical part, each projection having two radially spaced bearings, a segment of an 75 annular grate portion rockably supported on each pair of radial bearings and means for simultaneously rocking the segmental portions. 80

2. A device for burning coal comprising a fire pot having an inwardly extending 85 ledge and a central vertical support, a grate consisting of a plurality of sectors which, when assembled form a cone whose apex is upwards, the upper end of each sector having a projection at its top for engaging the 90 support and a projection at its base that extends radially and lies in a plane that is perpendicular to the axis of the cone, the outer ends of the radial projections extending over onto the ledge, each radial projection having two spaced bearings, a section of an annular grate ring supported on each 95 pair of bearings, the several sections being each mounted to rock about a radial axis, and means for simultaneously rocking all of 100 the annular grate sections.

3. A device for burning coal comprising, a fire pot having an inwardly extending ledge and a central vertical support, a grate consisting of a plurality of sectors which, when assembled form a cone whose apex is upwards, the upper end of each sector having a projection at its top for engaging the 105 support and its base provided with a radial projection that lies in a plane perpendicular to the axis of the cone, the outer ends of the radial projections extending over onto the ledge, each radial projection having two spaced bearings, a section of an annular 110

grate ring supported on each pair of bearings, the several sections forming an annular grate in which each section is mounted to rock about a radial axis, and means for simultaneously rocking all of the sections, 115 said means comprising a ring mounted for rotation about the vertical support, the ring having a radial projection for each grate section and each grate section having two spaced fingers that project downwardly one 120 on each side of a projection, and means for oscillating the ring whereby the grate sections will be rocked about their radial axes. 125

In testimony whereof I affix my signature.

OLIVER S. BOWMAN. 130
